UNITED STATES PATENT OFFICE.

JOHN A. FRETWELL, OF BRADFORD, ARKANSAS.

CONVERTIBLE RIDING, DRIVING, AND VETERINARY BRIDLE-BIT.

1,240,041.

Specification of Letters Patent. Patented Sept. 11, 1917.

Application filed July 25, 1916. Serial No. 111,298.

To all whom it may concern:

Be it known that I, JOHN A. FRETWELL, a citizen of the United States, residing at Bradford, in the county of White and State 5 of Arkansas, have invented certain new and useful Improvements in Convertible Riding, Driving, and Veterinary Bridle-Bits; and I do hereby declare the following to be a full, clear, and exact description of the invention, 10 such as will enable others skilled in the art to which it appertains to make and use the same.

The invention relates to a convertible riding, driving and veterinary bridle bit.

15 The object of the present invention is to improve the construction of bridle bits and to provide a simple, practical and efficient bridle bit of comparatively inexpensive construction and of the old English riding bit 20 type equipped with a mouth bar composed of fixed and relatively adjustable members adapted to be arranged in a variety of positions to enable the bit to be used as a non-clenchable bit, a graduating curb bit, a 25 drenching bit and a speculum for veterinary purposes.

A further object of the invention is to provide a bridle bit of this character adapted 30 to have its adjustable member of the mouth bar arranged to form a curb bit of different sizes and for moderate and severe curbing.

Another object of the invention is to 35 enable the adjustable member of the mouth bar to be arranged in different positions for forming a speculum of different sizes and a drenching bit of different sizes and also to permit free action of the tongue of the animal when it is desired to permit the same to swallow in administering medicine to the 40 same.

It is also an object of the invention to provide a convertible and adjustable bit having a medicine receiving chamber in its mouth bar adapted to permit any suitable medicine 45 or antiseptic or the like to be supplied to horses and cattle so that the same will gradually ooze out owing to the action of the saliva.

A further object of the invention is to 50 provide an interlocking construction for holding the adjustable member of the mouth bar when the bit is arranged for both curbing and to form a speculum so that there will be no liability of the said adjustable 55 member accidentally slipping or becoming loose.

With these and other objects in view, the invention consists in the construction and novel combination of parts hereinafter fully described, illustrated in the accompanying 60 drawing, and pointed out in the claims here- to appended; it being understood that various changes in the form, proportion, size and minor details of construction, within the scope of the claims, may be resorted 65 to without departing from the spirit or sacrificing any of the advantages of the in- vention.

In the drawings—

Figure 1 is a side elevation of a con- 70 vertible riding, driving and veterinary bridle bit constructed in accordance with this invention, and shown arranged for rid- ing or driving,

Fig. 2 is a vertical sectional view of the 75 same, the movable member of the mouth bar being arranged to form a drencher bit,

Fig. 3 is a transverse sectional view of the same,

Fig. 4 is a transverse sectional view of 80 the bit showing the same arranged to form a non-clenchable bit,

Fig. 5 is a detail sectional view illustrating the arrangement of the adjustable mem- 85 ber to form a speculum,

Fig. 6 is a sectional view illustrating the arrangement of the adjustable member of the mouth bar to form a curb bit,

Fig. 7 is a detail sectional view illustrating the construction of the medicine 90 chamber.

Like numerals of reference designate 95 corresponding parts in the several figures of the drawings.

In the accompanying drawings in which 100 is illustrated the preferred embodiment of the invention, the convertible, riding, driv- ing and veterinary bridle bit comprises in its construction two side frames 1 and a connect- ing mouth bar composed of fixed and 105 relatively movable sections 3 and 4. The bit which is of the old English riding type is designed to be constructed of steel or other suitable material and the relatively fixed section or member of the mouth bar is rigidly 110 secured at its terminals to the side frame at a point intermediate of the ends thereof preferably above the central portions of the same as clearly shown in Fig. 2 of the draw- ings. The members 3 and 4 of the mouth bar 115 are curved longitudinally and the relatively fixed member presents an upper convex edge

or face and a lower concave edge or face is also provided with a longitudinal groove or channel 5 which is adapted to form a medicine chamber for containing any suitable medicine or antiseptic which it may be desired to supply to horses and cattle for the treatment or prevention of diseases and ailments. The relatively adjustable member 4 which is substantially oval in cross section is adapted to be arranged contiguous to and in substantial parallelism with the relatively fixed member 3 to close the groove or chamber 5 for confining the medicine which may be arranged in the form of a paste or a more or less solid condition so as to be acted on by the saliva of the animals as required for any special treatment. The relatively movable member is also adapted to be adjusted or reversed to arrange its concave edge or face uppermost and its convex edge lowermost as illustrated in Fig. 4 of the accompanying drawings to form a non-clenchable bit which will effectually prevent an animal from taking the bit in his teeth and running away. By a non-clenchable bit it is to be understood that it is a bit which will render it impossible for a horse to rigidly hold the bit between its teeth and thereby preventing the rider or driver from controlling the animal by the bit.

The adjustable member 4 is provided at its ends with rectangular lugs 6 and it has threaded stems or portions 7 located beyond the lugs 6 and adapted to receive thumb nuts 8 which are preferably of the form shown but any other suitable configuration of adjusting nut may of course be employed. The side frames of the bit are enlarged at their central portions and are provided with approximately semi-circular slots 9 which are adapted to enable the relatively adjustable member of the mouth bar to be transferred from the upper to the lower portion of the side frames to convert the bridle bit into a drenching bit and also into a speculum. The side frames are also provided with upper extension slots 10 and lower extension slots 11 and they have an intermediate bracing or connecting portion 12 located adjacent to the terminal portions of the approximately semi-circular slots 9 to form a rigid structure and enable the bridle bit to be subjected to relatively great pressure without the liability of the bit collapsing or bending under the strain incident to its use when the bridle bit is employed either for riding, driving or for veterinary purposes in operation upon horses or cattle.

The slots are of a size to snugly receive the rectangular guide lugs 6 and the curved slots are provided intermediate of their ends with enlargements 13 which are of sufficient size to permit the relatively movable mouth bar to be rotated to change its position with

relation to the relatively fixed mouth bar so as to present either a convex or a concave surface to the mouth of the animal interiorly or exteriorly of the same.

The upper extension slot 10 is formed in an arm 14 of the side frame and it is approximately inverted U-shaped as shown and it is provided with recesses or notches 15 and 16 adapted to receive the rectangular guide stud of the movable member of the mouth bar and located different distances from the relatively fixed member of the mouth bar and capable also of permitting the relatively movable member to be reversed to arrange either the convex or the concave edge or face in position to be presented to the under side of the jaw of a horse to form either a moderate or severe curb as required. After the relatively movable member of the mouth bar has been adjusted in proper position in one of the notches or recesses 15 and 16 it is rigidly held in such position by adjusting the thumb nut.

The adjustable member of the mouth bar is adapted to be arranged at the lower portion of the curved or approximately semi-circular slot 9 to form a drenching bit as illustrated in Fig. 2 of the drawings and when in this position the adjustable member, which is rigidly secured by the clamping nut in the angle formed by the slots 9 and the lower branches or extensions 11 of said slots 9 presents a lower concaved face to the lower jaw and provides ample space for the action of the tongue to enable the animal to swallow the medicine delivered to it.

The extensions 11 of the slots 9 formed in the lower portions of the side frames are straight and are provided at spaced points with branch slots 17 and 18 which have notches 19 and 20 adapted to receive the guide lugs of the relatively adjustable member of the mouth bar whereby the latter is firmly interlocked with the side frames and is adapted to be rigidly secured to the same by the thumb nut to form a speculum but the upper slot may be also employed for holding the mouth of a horse or other animal open for drenching purposes as it will permit an easier introduction of the medicine into the mouth of the animal. While two branches extending from the extension slot 11 at right angles thereto, are illustrated in the accompanying drawing, any desired number of adjustments may of course be employed and when the bridle bit is employed as a speculum for veterinary purposes the upper and lower jaws of the animal are securely lashed to the bridle bit by passing a strap through upper and lower openings 21 and 22 provided in the terminal portions of the side frames at the top and bottom thereof and when the bit is secured in the mouth of an animal in this manner the jaws will be held rigidly against opening or closing.

movements and any operation may be performed with accuracy and security and access to all portions of the mouth of an animal may be had. The upper opening 21 is 5 adapted to receive the head stall when the bit is used for riding and driving and an intermediate slot 23 is provided in each of the central enlargements of the side frames to receive the reins or lines for driving and 10 also to receive a head stall when the device is arranged for use as a speculum. The side frames are also provided with upper and lower slots 24 and 25. The upper slot 24 is 15 adapted to receive an ordinary leather old style curb strap and the lower slots 25 of the side frames are adapted to receive the lines or reins for riding. Also the fixed and relatively adjustable members of the mouth bar enable the bit to be arranged as a graduating 20 bit for driving two horses with the same rein pressure and it frequently happens in practice in driving pairs that one horse pulls much harder on the bit than the other or the latter has what is called a "tenderer mouth." 25 By adjusting the position of the movable member of the mouth bar, the "feel" may be so regulated that the same pull on the reins will have the same effect with both horses. This will compensate for the difference 30 between a horse having a very hard mouth and another horse having a very tender mouth.

It will also be seen that the movable member may be arranged to apply any desired pressure under the chin of the animal and 35 that if the movable member be adjusted to present the arch or convex portion to the chin of the animal a very powerful pressure may be applied as may be required, for instance in breaking in a horse. On the other 40 hand the movable member may be turned to a reverse position to present the concaved side of the bar or member to the chin of the animal and the mouth bar will be in position to produce a moderate curbing of the 45 animal. In addition to the adjustment shown it will be clear that the arrangement of the slots and the extensions are such as to permit a relative adjustment of the members of the mouth bar to space them the desired 50 distance apart and to arrange them in the desired relative position to secure the required action on the mouth or jaws of an animal for riding, driving and also for veterinary purposes.

55 What is claimed is:—

1. A bridle bit of the class described comprising side frames provided with enlarged intermediate portions having approximately semi-circular slots provided with upper 60 branch slots and lower branch slots extending upwardly and downwardly from the said semi-circular slots at spaced points, a mouth bar composed of a fixed member rigidly connected with the sides at the upper 65 portions of said slots, and a relatively ad-

justable member having portions guided in the said slots and movable also into the upper and lower branch slots to form a curb bit, a drenching bit and a speculum.

2. A bridle bit of the class described including spaced side frames provided with enlarged intermediate portions having upwardly projecting arms inclined to the vertical, said intermediate portions being also provided with approximately semi-circular slots, and said arms having branch slots forming extensions of the slots of the intermediate portions, and a mouth bar composed of a relatively fixed member rigidly connected with the side frames at the upper 70 portions of the said slots, and a relatively movable member operating in the said slots and also in the branch slots to form a curb bit and also a drenching bit.

3. A bridle bit of the class described including side frames provided with slots and having approximately inverted U-shaped branch slots forming extensions of the said slots and provided with notches or recesses located at different distances from the terminals of the same, said branch slots being located adjacent the horizontal plane of the upper terminals of the first mentioned slots, and a mouth bar composed of a relatively fixed member rigidly connected with the 85 side frames, and a relatively movable member adjustable in the said slots and in the branches thereof and provided with means for securing its terminals in the said recesses or notches to form a curb bit.

4. A bridle bit of the class described comprising side frames provided with approximately semi-circular slots having straight lower vertical longitudinal branch slots extending downwardly from the lower ends of the semi-circular slots, said branch slots being provided with angularly related branches disposed at intervals, and a mouth bar comprising relatively fixed and movable members, the movable member being guided in 100 the said slots and adapted to be arranged in the said branch slots and the branches thereof to form a speculum.

5. A bridle bit of the class described including side frames provided with approximately semi-circular slots having lower straight vertical branch slots extending from the lower ends of the said semi-circular slots, said branch slots being provided with angularly related branches located at spaced 115 points and having terminal recesses, and a mouth bar composed of fixed and movable members, the movable member being operable in the said slots and provided with means for securing it in the said recesses to 120 form an adjustable speculum.

6. A bridle bit of the class described including spaced side frames having enlarged intermediate portions provided with upwardly extending arms inclined to the ver- 130

tical; said side frames being also provided in their intermediate portions with curved slots having upper and lower branch slots, the upper branch slots being formed in the 5 said arms and the lower branch slots extending downwardly longitudinally of the side frames of the intermediate enlarged portions, said branch slots having recesses spaced apart, and a mouth bar composed of 10 relatively fixed and movable sections, the movable section being operable in the said slots to and adapted to be supported by the said arms spaced from and in approximately the same horizontal plane as the fixed section and provided with means for securing 15 it in the said recesses, whereby an adjustable curb and an adjustable speculum may be formed.

7. A bridle bit of the class described in-

cluding spaced side frames having top and 20 bottom openings and provided with upper, lower and intermediate slots, said side frames being also provided with curved slots having upper and lower branch slots provided with spaced notches, the upper branch 25 slots having portions inclined to the vertical and the lower branch slots extending longitudinally of the side frames, and a mouth bar composed of fixed and movable members, the movable member operating in 30 the curved slots and the extensions thereof and provided with means for securing it in the said notches to arrange the movable member at different distances from the relatively fixed member and in different positions with relation to the same.

In testimony whereof I affix my signature.

JOHN A. FRETWELL.
